UNITED STATES PATENT OFFICE.

CHARLES C. KELLY AND JULIUS COBB, OF ST. PAUL, MINNESOTA.

IMPROVEMENT IN ENVELOPES.

Specification forming part of Letters Patent No. **149,484**, dated April 7, 1874; application filed March 6, 1874.

To all whom it may concern:

Be it known that we, CHARLES C. KELLY and JULIUS COBB, of St. Paul, in the county of Ramsey and State of Minnesota, have invented a new and Improved Envelope; and I do hereby declare that the following is a full, clear, and exact description of the same, reference being had to the accompanying drawing forming a part of this specification, in which—

Figure 1 represents a plan of the envelope before it is folded. Figs. 2 and 3 represent the same partially folded, and Fig. 4 the same folded complete.

The invention relates to the construction of package-envelopes, so as to make them more secure and reliable.

The invention will first be fully described, and then pointed out in the claim.

A represents the central rectangular piece or body of the envelope, B B' the end flaps, and C C' the side flaps. The side flap C is made, preferably, rectangular, although it may be rounded at the corners, if so desired. It is the first flap folded, and has two longitudinal slits, c c, that receive the heads c¹ c¹ of the opposite side flap c¹, which is folded next. The third flap folded is the end one B, which

has a head, b, which passes through the two transverse slits c² c³ in the side flaps. The end flap B' is the last one which is folded upon the others, its head b¹ passing through the three transverse slits b² c⁴ c⁵. Each of the heads b b¹ c¹ has a maximum width toward the base which exceeds that of the slit into which it fits, and is recessed under and on each side of this base. This allows the formation of wings that turn and are readily inserted, while, after insertion, they become catches to hold together the connected parts.

Having thus described our invention, what we claim is—

As an article of manufacture, a package-envelope consisting of body A, end flaps B B', and side flaps C C', the said flaps having heads b b¹ c¹ and slits b² c² c³ c⁴ c⁵, constructed and arranged as and for the purpose specified.

The above specification of our invention signed by us this 7th day of January, A. D. 1874.

CHARLES C. KELLY.
JULIUS COBB.
